UNITED STATES PATENT OFFICE.

HENRY M. ETTER, OF MARION, PENNSYLVANIA.

DESIGN FOR A PUMP-HEAD.

SPECIFICATION forming part of Design No. 32,643, dated May 8, 1900.

Application filed April 12, 1900. Serial No. 12,642. Term of patent 7 years.

To all whom it may concern:

Be it known that I, HENRY M. ETTER, a citizen of the United States, residing at Marion, in the county of Franklin and State of Pennsylvania, have invented and produced a new and original Design for a Pump-Head, of which the following is a specification.

The accompanying drawing is a perspective view of the pump-head.

- 10 A gooseneck-shaped nozzle projects from a swell at the circular base *a*, at the upper end of which is a rectangular horizontal stand *b*, supporting two vertical parallel members *c c*, which rise from the stand. These two members have flat sides, with both edges straight
- 15 at the lower portion and each member hav-

ing at the upper portion of its edges oppositely-projecting brackets *d d'*, whose upper and lower edges are curved, and a rectangular flat cap *e*, surmounting the said two members.

Having thus described my invention, what I claim is—

The design for a pump-head as herein shown and described.

In testimony whereof I affix my signature in the presence of two witnesses.

HENRY M. ETTER.
